UNITED STATES PATENT OFFICE

171,464

COMBINED DOOR KNOCKER AND BELL

Sajjan Singh Sarna, New York, N. Y., assignor to S. S. Sarna, Inc., New York, N. Y., a corporation of New York

Application June 15, 1953, Serial No. 25,479

Term of patent 14 years

(Cl. D72—1)

To all whom it may concern:

Be it known that I, Sajjan Singh Sarna, a citizen of the United States of America, residing at New York, State of New York, have invented a new, original, and ornamental Design for a Combined Door Knocker and Bell, of which the following is a specification, reference being had to the accompanying drawings, forming a part hereof.

Fig. 1 is a front elevational view of a combined door knocker and bell showing my new design;

Fig. 2 is a rear elevational view thereof;

Fig. 3 is a side elevational view;

Fig. 4 is a top plan view;

Fig. 5 is a bottom plan view; and

Fig. 6 is a cross-sectional view taken on the line 6—6 of Fig. 1.

I claim:

The ornamental design for a combined door knocker and bell, as shown.

SAJJAN SINGH SARNA.
